ATTORNEY.

UNITED STATES PATENT OFFICE.

ORA BILLINGSLEY, OF NEW YORK, N. Y.

LOCK.

Application filed December 17, 1925. Serial No. 75,903.

This invention relates to locks and particularly to locks of the key-less type.

This invention is an improvement of my invention set forth in my copending application Serial No. 50,912, filed by me on August 18th, 1925, entitled Keyless combination lock.

A feature of the present invention is the provision of suitable means for precluding 10 the "shaking" or "wobbling" of any dial member relative to any associated lock part in any illegitimate attempt to decipher the combination, while permitting the dial members, their locking devices and the coacting 15 elements of the lock to be formed of approximately fitted parts.

Pursuant to the present invention, my lock embodies a set of dial members rotatively mounted in a hollow casing member, 20 a movable lock member or equivalent which is provided with a circularly extending or annular groove combined with a groove communicating with said annular groove and extending tangentially therefrom, each of said 25 dial members carrying a set of pins or equivalent; one of said pins which may be termed the "main" pin extends into its annular groove, and another pin positioned at right angles to said first-named pin, said another 30 pin traversing the tangential groove when the first-named pin is in its lock opening position. Such set of pins for each dial member positively prevents the "shaking" or "wobbling" of any dial member for all its 35 positions of rotative movement and particularly when its main pin is in its opening position.

Further features and objects of the invention will be more fully understood from the 40 following detail description and the accompanying drawings, in which

Fig. 1 is a front elevation of a drawer of a desk or the like, showing my improved form of lock proper thereto; Fig. 2 is a 45 sectional elevation on line 2—2 of Fig. 1; Fig. 3 is a sectional elevation on line 3—3 of Fig. 2; and Fig. 4 is a sectional elevation on line 4—4 of Fig. 3.

Fig. 5 is a front elevation showing a modified form of my lock applied to a vanity case, jewelry case or the like, and illustrating a similar use for suitcases and other hand luggage; Fig. 6 is a sectional elevation on line 6—6 of Fig. 5; Fig. 7 is a sectional

elevation taken on line 7—7 of Fig. 6, on a somewhat enlarged scale; and Fig. 8 is a sectional elevation on line 8—8 of Fig. 7.

Fig. 9 is a front elevation of another form of my improved lock illustrated as applied to the drawer of a desk or the like;

Fig. 10 is a sectional elevation on line 10—10 of Fig. 9; and

Fig. 11 is a sectional elevation on line 11—11 of Fig. 10.

Referring to Figs. 1 to 4, inclusive, the drawer 15 may be of a desk 16, bureau or other form of furniture, or may be a safe deposit box or the like. Such drawer 15 is usually provided with a hand-grasp 17.

In the form of my invention illustrated in these figures, the casing member 18 and the movable lock member 19 are located interiorly of the front board 20 of the drawer 15, as appears in Figs. 2 and 4. The casing member 18 comprises the front plate 21 and rear plate 22, the latter of which is preferably enlarged at its opposite lateral ends as is indicated at 23, 24, which enlarged lateral ends 23, 24, are provided with suitable openings registering with corresponding openings in the front plate 21 for receiving the screws 25 for securing the casing member 18 to the inner face of the front board 20 of the drawer 15.

The movable lock member 19 makes a sliding fit with the inner faces of the enlarged lateral ends 23, 24. Such form of my improved lock as applied to drawers, the movable lock member 19 is given a limited movement; the extreme outward position of the movable lock member 19 takes place when the lock is in its closed position, as is indicated in Figs. 2, 3 and 4. When the lock is in its open position, the movable lock member 19 drops from the position shown in Figs. 2 and 3, to bring its upper edge 26 substantially flush with the upper edge of the casing member 18, to thereby clear the movable lock member 19 and permit the drawer to move

outwardly of the drawer opening.

As is set forth in my aforesaid copending application, Serial No. 50,912, the movable lock member 19 is provided with a set of annular grooves of a number corresponding to the number of the set of manually operated dial members; in this instance the annular grooves and dial members are three in number and the annular grooves are des-

55

105

ignated 27, 28, 29. The knurled heads of the three dial members are designated 30, 31, 32.

Each of the three dial members is mounted 5 in a suitable opening 33 in the front board 20 of the drawer 15, and the escutcheon plate 34 is provided with corresponding openings for the respective dial members 30, 31, 32. The escutcheon plate 34 is secured on the 10 front or outer face of the front board 20 of the drawer 15 by the screws 35 or equivalent.

The body portion 36 of each dial member 15 30, 31, 32 is substantially cylindrical and of a diameter slightly less than its opening 33 in the front board 20. The dial plate 37 of each dial member is preferably circular and of a diameter slightly larger than its opening 33. The designation on each dial member 20 37 may be in numbers, letters or of any desired codifications.

Each dial member is further provided with a stud 38 at its rearward end, which in this type of my invention passes through a 25 suitable opening in the rear plate 22 of the lock casing 18. The rear end of each stud 38 is threaded to receive a nut 38^a, to thereby lock each dial member in position. To afford the desired movement of the movable 30 lock member 19 in the opening and closing of the same relative to the lock casing 18, the lock member 19 is provided with a set of recesses 39 in the form of perforated slots.

As above indicated, the lock member 19 is 35 of restricted movement and accordingly the slots 39 are of limited length as appears in the left-hand and right-hand slots 39 shown in Fig. 3. The central slot 39^a is not illustrated of restricted length, for the reason 40 that it functions with supplemental means for manually lifting and lowering the movable lock member 19 when desired, and as explained more fully hereinafter.

Pursuant to the present invention, the rear 45 face 40 of the body portion 36 of each dial member is provided with a locking device in the form of a main pin 41 removably positioned on such rear face 40 at a location corresponding to its number factor of the combination of the lock and to project into its annular recess 27, 28, or 29. Such pin 41 is usually secured by inserting the pin in a suitable opening on the rear face 40, which opening may be threaded or the pin may be secured 55 therein by a tight fit.

Pursuant to the present invention, such locking device further comprises the supplemental pin 42 similarly secured to the rear face 40 of the body portion 36 of each dial member and such supplemental pin 42 is positioned relative to its main pin 41 to be located substantially at the angle of 90° therefrom, whereby when its main pin 41 is moved to its opening position, i. e., in alignment 60 with its lock-opening slot 39 or 39^a, the sup-

plemental pin 42 is disposed in alignment with its tangential groove 43. Such tangential grooves 43, as appears in the left-hand and central grooves of the slidable member 19 of the lock, may be to the right of the respective slots 39, 39^a, or may be to the left of the same, as appears for the right-hand groove 29 and its tangential groove 43. Such tangential groove 43 communicates with its annular groove 27, 28 or 29 at a 70 75 80 90° relationship to the point of communication of its slot 39 with its annular groove; the tangential grooves 43 extend from such points of communication substantially parallel to their associated slots 39, 39^a and are of similar lengths and closed ended.

By the provision of such tangential grooves 43, upon positioning the main locking pins 41 in their respective unlocking positions, and upon moving the slidable lock 85 member 19 from its locking position to its unlocking position, the supplemental pins 42 are moved respectively in their tangential grooves 43, and, conversely, when the movable lock member 13 is moved from its unlocking position to its locking position, preparatory to moving the dial members to their locking positions.

By the arrangement of the mutually related pins 41, 42 for each dial member, when 90 any dial member is in its lock-closing position, irrespective of the positions of the pins 41, 42 of the other dial member or dial members, the movable lock member 19 is positively held against wobbling or sideplay. This feature is of importance for the reason 95 that it precludes the detection by unauthorized persons of the "combination" of the lock, even though the dial members may be turned gradually or otherwise by such unauthorized person to varying positions in the attempt to ascertain the position of each main locking pin 41 when in alignment with its slot 39 or 39^a. Such feature also permits 100 the construction of locks embodying my invention for effectual protection against unlocking by the employment of main locking pins 41 and supplemental locking pins 42 having but a loose fit respectively in the annular grooves 27, 28, 29, thereby obviating 105 undue nicety of fit of these parts relatively to one another.

An auxiliary feature appears in the above 110 form of my invention, namely in the provision of the manually opening and closing member 44 which in appearance may simulate one of the aforesaid dial members, but in lieu of numerical or scale markings bears an arrow 45 with or without the legend "Open" 115 to indicate the direction of rotation of the member 44 for raising the movable lock member 19, and for lowering the movable lock member 19 in the opposite direction. Such auxiliary member 44 may have a body portion 46 corresponding to the body por- 120 125 130

tion 36 of the aforesaid dial members and extend through an opening 47 in the front board 20 of the drawer 15. The rear face of the body portion 46 is provided with the 5 central stud 48 extending through the upper portion of the perforated slot 39^a and close-ended at 49 at a location corresponding to the range of movement of the movable lock member 19. The coacting pin 50 is located 10 on the rear face 46 of the manual member 44 adjacent its peripheral edge and extends through the lateral, perforated slot 51 which may communicate at 52 with the aforesaid slot 39^a. The central stud 48 is locked by 15 its nut 48^a.

Upon turning the manual member 44 in the direction of the arrow 45, the pin 50 is displaced upwardly by its rotation upwardly relatively to its central stud 48, which 20 movement is accompanied by a displacement of the pin 50 to the left, see Fig. 3, in its slot 51, and the upward movement of the stud 48 relative to the slot 39^a. The turning of the manual member 44 in a direction opposite 25 to the arrow 45 effects the opposite movements of the pin 50 relative to its slot 51 and the opposite movement of the stud 48 relative to its slot 39^a.

In the modification shown in Figs. 5 to 8, 30 inclusive, the aforesaid construction of my improved lock is similarly embodied and like parts are designated by like reference characters. However, in this form of my lock, the perforated slots 39 are all of uniform 35 length and are located to be in substantial alignment with one another, thus providing for the movement of the movable lock member 19, see Figs. 5 and 7, in the counter-directions indicated by the double arrowed 40 line 55, applicable for use with a co-acting pivotally mounted lock member 56, having a locking lug 57 provided with a slot 58 for receiving the locking end 59 of the movable lock member 19. The movable lock 45 member 19 is preferably biased to its locking position, as by means of a spring 60, usually of flat stock and having an angular formation as indicated in Fig. 7 and loosely held in position between the edge 61 50 of the movable lock member 19 and the inner wall 62 of the lock casing member 18. Such pivotal lock member 56 may be of a metal stamping having the oppositely disposed pivot ears 63, the openings of which 55 are in alignment with the opening of the eye 64 of the base 65, for receiving a pintle 66. The base 65 is secured by the rivets 65^a to the front lateral edge 67 of the top 68 of the suitcase, vanity case, jewel box or the 60 like.

Such arrangement of the dial members, the movable lock member 19 and the coacting locking member 56 attains a lock construction which is greatly reduced in the 65 dimensions of the respective parts, thereby

affording the employment of "miniature" dial members, as is desirable for vanity cases, jewel boxes, brief cases and the like.

The casing member 18 of the lock is secured to the front flange 69 of the bottom 70 of a suitcase, vanity case, jewel box or the body of a brief case or the like by means of the screws 70 extending from the inner face of the flange 69 into the tapped or internally threaded lugs 71 projecting from 75 or cast with the rearward faces of the enlarged edge portions 72 of the lock casing 18. It will be observed that the barrel portions of the dial members may in this instance be of relatively reduced length and that the circular dial flanges 73 are rabbed as is indicated at 74 inferiorly within the front member 21 of the lock casing 18, to be thereby individually locked against 80 forceful displacement outwardly of the front plate 21 of the lock casing 18. Such construction also obviates the need of locking the respective studs 38 of the dial members at their rearward ends, as in the aforesaid constructions shown in Figs. 1 to 4, in- 85 clusive.

To afford manual opening of the movable lock member when in its unlocked position, I provide the pin 75 secured to and extending forwardly of the movable lock member 19 through the slot 76 in the front plate 21 of the lock casing 18. Such pin 75, see Fig. 6, may be provided with a spherical head 77, to facilitate manual grasping. 90

In the modification shown in Figs. 9, 10 95 and 11, applicable for use to a drawer or a desk or the like, the dial members, the movable lock member and the casing member are of reduced dimensions similar to the construction shown in the modification of Figs. 5 to 8, inclusive, and like parts are designated by like reference characters. 100

However, in the modification of Figs. 9, 10 and 11, the locking end 59 of the movable lock member 19 projects through the slot 78 through the upper side strip 79 of the casing member 18 of the lock to be received within the slot opening 80 of the co-acting lock plate 81 when the movable lock member 19 is moved to its locking position, 110 and withdrawn therethrough when displaced to its unlocking position. The co-acting lock member 81 may be a metal stamping having a bottom plate 82 provided with suitable openings for the screws 83 passing upwardly through the front apron board 84 of the desk 16 or the like. 115

A manually operated opening and closing member simulating a locking dial member, similar to the construction shown in the aforesaid modification of Figs. 1 to 4, inclusive, but of correspondingly reduced body portion, is also employed in the modification of Figs. 9 to 11, inclusive, and like parts are designated by like reference numbers. 120 125 130

In addition, the manually opening and closing member differs from the aforesaid form appearing in Figs. 1 to 4, by the omission of any central stud 48, for the reason that the body portion of the manual opening and closing member 44, as appears in Figs. 9, 10 and 11, is locked by rabbeting as indicated at 85, see Fig. 10, within the outer plate 21 of the lock casing 18 against outward displacement, while permitting rotation of the body portion 46 of the manually operated member 44. In this instance the pin 50 at the rear face of the body portion 46 of the member 44 is received within a groove 51^a which need not be a perforation and corresponding to the aforesaid perforated slot 51 appearing in Fig. 3, whereby upon movement of the manual member 44 and therewith of the body portion 46 in the direction of the arrow 86, see Figs. 9 and 11, the pin 50 is moved downwardly when the locking pins 41 of the dial members are all in their unlocking positions, in which movement the respective pins 41 are moved in their longitudinal grooves 39. It will be noted that in such construction, as appears in Fig. 11, the central groove 39 has a length which is uniform with the right-hand and left-hand grooves 39 and that such grooves 39 need not be perforated.

From the above, it will appear from the several forms of my present invention, I have provided a keyless lock which is opened and closed by "combinations" of variable setting by numbers, letters or other codified indications. For obtaining or for changing the various combinations, the main locking pin 41 is changed in its position at the circumference represented by the center line of its substantially circular groove in the movable lock member 19 and relative to the "0" or other initial scale marking; its coating pin 42 is correspondingly positioned to the desired right angular relationship therewith. For such purpose, the rear face 40 of each dial member may be provided with a set of recesses spaced from one another as desired and the pins 41, 42 positioned either by tight frictional fit or by meshing screw-threading. It will be observed that the parts of the lock, when in their open positions are readily disassembled to permit the combination of the lock to be changed whenever desired, and as readily re-assembled and positioned on the drawer or suit-case, vanity case, jewel box, brief-case or the like.

Whereas, I have described my invention by reference to specific forms thereof, it will be understood that many changes and modifications may be made without departing from the spirit of the invention.

I claim:

1. In a keyless lock, the combination of a hollow casing member, a set of dial members movably mounted in said casing member, a

movable lock member movably disposed within said hollow casing member, said movable lock member being provided with a set of substantially circularly extending grooves of a number corresponding to that of said set of dial members, said movable lock member being further provided with a groove communicating tangentially with each of said substantially circularly extending grooves, said movable lock member being further provided with a set of recesses corresponding in number to said set of dial members, each of said last-named recesses communicating with its substantially circularly extending recesses and extending radially therefrom and a set of locking elements respectively carried by said dial members and extending within said substantial circularly extending recesses respectively.

2. In a keyless lock, the combination of a hollow casing member, a set of dial members movably mounted in said casing member, a movable lock member movably disposed within said hollow casing member, said movable lock member being provided with a set of substantially circularly extending grooves of a number corresponding to that of said set of dial members, said movable lock member being further provided with a groove communicating tangentially with each of said substantially circularly extending grooves, said movable lock member being further provided with a set of recesses corresponding in number to said set of dial members, each of said last-named recesses communicating with its substantially circularly extending recesses and extending radially therefrom and a set of locking elements respectively carried by said dial members in substantially right angular relationship with one another and extending within said substantial circularly extending recesses respectively.

3. In a keyless lock, the combination of a hollow casing member, a set of dial members movably mounted in said casing member, a movable lock member movably disposed within said hollow casing member, said movable lock member being provided with a set of substantially circularly extending grooves of a number corresponding to that of said set of dial members, said movable lock member being further provided with a groove communicating tangentially with each of said substantially circularly extending grooves, said movable lock member being further provided with a set of recesses corresponding in number to said set of dial members, each of said last-named recesses communicating with its substantially circularly extending recesses and extending radially therefrom, said tangentially communicating grooves extending substantially parallel to one another and a set of locking elements respectively carried by said dial

members and extending within said substantial circularly extending recesses respectively.

4. In a keyless lock, the combination of 5 a hollow casing member, a set of dial members movably mounted in said casing member, a movable lock member movably disposed within said hollow casing member, said movable lock member being provided 10 with a set of substantially circularly extending grooves of a number corresponding to that of said set of dial members, said movable lock member being further provided with a groove communicating tangentially 15 with each of said substantially circularly extending grooves, said movable lock member being further provided with a set of recesses corresponding in number to said set of dial members, each of said last-named 20 recesses communicating with its substantially circularly extending recesses and extending radially therefrom, said tangentially communicating grooves extending substantially 25 in alignment with one another and a set of locking elements respectively carried by said dial members in substantially right angular relationship with one another and extending within said substantial circularly extending recesses respectively. 81

5. In a keyless lock, the combination of a 30 hollow casing member, a set of dial members movably mounted in said casing member, a movable lock member movably disposed within said hollow casing member, said movable lock member being provided with a set of substantially circularly extending grooves of a number corresponding to that of said set of dial members, said movable lock member being further provided with a groove communicating tangentially 35 with each of said substantially circularly extending grooves, said movable lock member being further provided with a set of recesses corresponding in number to said set of dial members, each of said last-named 40 recesses communicating with its substantially circularly extending recesses and extending radially therefrom, said tangentially communicating grooves extending substantially 45 parallel to one another and a set of locking elements respectively carried by said dial members in substantially right angular relationship with one another and extending within said substantial circularly extending recesses respectively. 100

6. In a keyless lock, the combination of a 50 hollow casing member, a set of dial members movably mounted in said casing member, a movable lock member movably disposed within said hollow casing member, said movable lock member being provided with a set of substantially circularly extending grooves of a number corresponding to that of said set of dial members, said movable lock member being further provided with a groove communicating tangen-

tially with each of said substantially circularly extending grooves, said movable lock member being further provided with a set of recesses corresponding in number to said set of dial members, each of said last-named 55 recesses communicating with its substantially circularly extending recesses and extending radially therefrom, said tangentially communicating grooves extending substantially 60 in alignment with one another and a set of locking elements respectively carried by said dial members in substantially right angular relationship with one another and extending within said substantial circularly extending recesses respectively. 71

7. In a keyless lock, the combination of a hollow casing member, a set of dial members movably mounted in said casing member, a movable lock member controlled jointly by said set of dial members, said movable lock member having a set of substantially circularly extending grooves of a number corresponding to that of said set of dial members, said movable lock member being provided with a groove communicating 75 radially with each of said circularly extending grooves at one location thereof and further with a groove communicating tangentially with each of said substantially circularly extending grooves at a location 80 disposed substantially ninety arcuate degrees from said one location and a set of variable locking elements respectively carried by said dial members, the locking elements of each set extending within one of said substantially circularly extending recesses. 95

8. In a keyless lock, the combination of a hollow casing member, a set of dial members movably mounted in said casing member, a movable lock member controlled jointly by said set of dial members, said movable lock member having a set of substantially circularly extending grooves of a number corresponding to that of said set of dial members, said movable lock member being provided with a groove communicating 100 radially with each of said circularly extending grooves at one location thereof and further with a groove communicating tangentially with each of said substantially circularly extending grooves at a location 105 disposed substantially ninety arcuate degrees from said one location and a set of variable locking elements respectively carried by said dial members, the locking elements of each set being in substantially ninety arcuate degree relationship to one another and extending within one of said substantially circularly extending recesses. 115

9. In a keyless lock, the combination of a hollow casing member, a set of dial members movably mounted in said casing member, a movable lock member controlled jointly by said set of dial members, said movable 120

lock member having a set of substantially circularly extending grooves of a number corresponding to that of said set of dial members, said movable lock member being provided with a groove communicating radially with each of said circularly extending grooves at one location thereof and further with a groove communicating tangentially with each of said substantially circularly extending grooves at a location disposed substantially ninety arcuate degrees from said one location, said tangential recesses extending substantially parallel to said radially extending recesses respectively, and a set of variable locking elements respectively carried by said dial members, the lock-elements of each set extending within said one of substantially circularly extending recesses.

10. In a keyless lock, the combination of a hollow casing member, a set of dial members movably mounted in said casing member, a movable lock member controlled jointly by said set of dial members, said movable lock member having a set of substantially circularly extending grooves of a number corresponding to that of said set of dial members, said movable lock member being provided with a groove communicating radially with each of said circularly extending grooves at one location thereof and further with a groove communicating tangentially with each of said substantially circularly extending grooves at a location disposed substantially ninety arcuate degrees from said one location, said tangential recesses extending substantially parallel to said radially extending recesses respectively, and a set of variable locking elements respectively

carried by said dial members, the locking elements of each set being in substantially ninety arcuate degree relationship to one another and extending within said one of substantially circularly extending recesses.

11. In a keyless lock, the combination of a hollow casing member, a set of dial members movably mounted in said casing member, a movable lock member movably disposed within said hollow casing member, said movable lock member being provided with a set of substantially circularly extending grooves of a number corresponding to that of said set of dial members, said movable lock member being further provided with a groove communicating tangentially with each of said substantially circularly extending grooves, said movable lock member being further provided with a set of recesses corresponding in number to said set of dial members, each of said last-named recesses communicating with its substantially circularly extending recesses and extending radially therefrom, a set of locking elements respectively carried by said dial members and extending within said substantial circularly extending recesses respectively, said movable lock member being further provided with an additional recess, a manually operated member for moving said movable lock member to its closing and opening position; and a pin carried by said manually operated member and extending into said additional recess.

In testimony whereof I have signed this specification this 19th day of Sept. 1925.

ORA BILLINGSLEY.
